BOX ELEVATOR

Albert E. Thompson, Los Gatos, and Roy M. Magnuson, Campbell, Calif., assignors to Food Machinery Corporation, San Jose, Calif., a corporation of Delaware

Application June 10, 1940, Serial No. 339,696

16 Claims. (Cl. 214—95)

This invention relates to handling and conveying articles such as packages, boxes, crates, and the like. After the disclosure of a machine in which the invention is embodied it will be apparent that this machine and other machines employing the inventive ideas disclosed herein could be adapted to handle a wide variety of articles other than those briefly enumerated above. To simplify this disclosure the article will be referred to as a box throughout, it being understood that this particular article is chosen merely for purposes of illustration.

The invention is disclosed as embodied in machines for handling boxes in warehouses, refrigerators, and the like. These boxes contain the material or articles which are to be placed in storage. The work of placing the boxes in storage usually involves: (1) transportation substantially horizontally; (2) elevation; (3) distribution substantially horizontally. And in the removal of the boxes from storage this process is reversed. These are the three basic steps in moving boxes into and out of a storage building of more than one floor and also of moving them into and out of piles or stacks of boxes on one floor.

Machines constructed in accordance with this invention are enabled to mechanically perform this work. Two embodiments will be disclosed herein: one is a mobile unit; the other is a permanent installation. The mobile unit can be moved down the narrow aisles of a warehouse, where space is at a premium, and can be maneuvered into close quarters to lift the boxes and deposit them on the top of the stack, or to remove them from the stack and lower them to the floor. The permanent installation is a special elevator built into the building to lift the boxes up to the floor on which they are to be stored, or to remove them therefrom.

One of the objects of my invention is to provide an improved elevator for boxes and the like.

Another object is to provide a box elevator with a device which will automatically load and unload it.

A further object is to provide a box elevator which will handle boxes right side up so as not to disturb the contents.

Still another object is to provide an elevator which will raise and lower boxes vertically.

A further object is to provide a box elevator which is adapted to be either mounted on a vehicle for mobility or installed permanently in a building.

General description

The mobile unit will hereinafter be referred to as a stacker. It comprises a vehicle 100 (Fig.

1) which supports a tower 300. Within this tower is an elevator 400. The box B is fed into the bottom of the elevator by a conveyor 200. Sets of elevator tines 401 pick the box up off the conveyor and lift it up in the tower by an intermittent motion derived from the driving mechanism 500 down in the vehicle.

An operator is stationed in a car 700 which he can position at the desired height on the stack side of the stacker. In the car is a transport 600 including a shifter 601 to transfer the box from the elevator to a conveyor 602, thus transporting the box from the elevator across to the top of the stack.

The mechanism of the stacker is completely reversible so that by pressing a button at the electric control 803 a reverse movement is obtained which enables the machine to remove boxes from the stack. The box is deposited on the conveyor 602 from which shifter 601 transfers it to elevator tines 401 which lower it down onto conveyor 200.

To facilitate identification of the parts of the machine certain broad divisions have been assigned distinctive series of numerals, such as the elevator 400 and its driving mechanism 500. Individual parts of each division bear reference numerals in the division series, as elevator tines 401.

Vehicle 100

At the end of the vehicle usually positioned adjacent the stack, which end will be referred to as the front end, are a pair of wheels 101, one of which appears in Fig. 6. The axle 102 of wheel 101 is suitably mounted beneath a frame member 103. There is a similar member 103 on the other side of the vehicle and the ends of these members are welded to a cross channel 104. Member 103 is bent outwardly at 105 and is attached inside a channel 106. There are two of these channels, one at each side of the vehicle (Fig. 7) and they are the outer longitudinal members of the main part of the frame. Lying parallel thereto and spaced inwardly therefrom are two more longitudinal members, the angles 107 and 108. The longitudinal members are tied together by fore and aft transverse channels 109 and 110 (Fig. 8). The four corners of this framework are reinforced with gusset plates 111 (Figs. 7 and 9). Caster wheels 112 (Figs. 6 and 7) are mounted at the rear corners of the frame.

A sub-frame is secured underneath this main frame. Its fore and aft transverse channels 120, 121 (Fig. 6) are fastened to transverse channels 109, 110 (Fig. 8) by bolts 122. The longitudinal angles 123, 124 (Fig. 7) are welded at their ends to transverse channels 120, 121 (Fig. 8). An angle 125 is welded to the vertical flange of angle 123 as shown in Fig. 7. When the bolts 122 are unfastened the sub-frame can be removed from the main frame. The angle 115 (Fig. 7) is not part of the sub-frame but is welded to longitudinal angle 108 so that its horizontal flange will be in the same plane as the horizontal flange of sub-frame angle 125 when the sub-frame is bolted in place on the main frame.

A base for tower 300 and conveyor 200 is built on the main frame. In each of the four corners of the frame vertical angles are welded. These posts 130, 131, 132, 133 (Figs. 6, 7 and 9) are welded at their upper ends into the corners of a framework formed by the two longitudinal angles 134, 135 (Fig. 7) and the two transverse angles 136, 137 (Fig. 6). Two other angles 138,

139 (Fig. 7) run longitudinally of the base frame. Their ends are welded to transverse angles 136, 137. Two transverse angles 140, 141 are secured at their outer ends to the angles 134, 135, respectively; and at their inner ends to angles 138, 139, respectively. Angles 140, 141 lie in the same transverse plane; 141 appearing in section where 135 is broken away in Fig. 6. Angles 140, 141 appear in elevation in Fig. 7 and a portion of 137 can be seen at the rear of the frame. Secured to angles 138, 139 at their middle are two short angles 142, 143, the latter appearing in elevation in Fig. 6. The two front posts 130, 131 each have a brace such as 145 attached at its upper end to post 131 and at its lower end to frame member 103.

The stacker is pushed or pulled into the position in which it is to operate, the caster wheels 112 being provided to facilitate maneuvering. If desired, the stacker could be propelled by power, in which event the wheels 101 would be driven from a source of power on the frame and the wheels 112 would be made steerable.

Conveyor 200

This is a conveyor of the gravity type. A series of rollers 291 (Fig. 1) are mounted in a two-section framework 292, the inner section of which is secured at its inner end to a narrow framework 293 in which short rollers 204 are mounted (Fig. 7). The front end of framework 293 is secured to the inner section of a framework similar to 292 having the long rollers 291. The two sections are detachable at 221, the outer section being numbered 220 (Fig. 1). When these five sections of framework are secured together they constitute a rigid framework for the conveyor as a whole which is pivoted on a shaft 206 journaled in angles 142, 143. A prop 207 (Fig. 1) pivoted at 208 has notches which can be engaged with the edge of the horizontal flange of angle 137 to position the conveyor 200 in various angular positions on its pivot 208.

The position shown in Fig. 1 is for introducing boxes into the elevator 400, limit stops 210 (Figs. 1 and 2) being provided to arrest box B in position to be lifted off the rollers by engagement of elevator tines 401 which are swung under the bottom edges of the box which extend out from short rollers 204 (Fig. 7), the conveyor having been narrowed at this point for this purpose. When the upper notch in prop 207 is engaged with angle 137 the conveyor is positioned so as to conduct the boxes out of the elevator after they have been lowered down onto the rollers by the elevator tines 401.

Sometimes it is desired to convey boxes through the machine without elevating them, as when placing boxes at the bottom of a stack near floor level. It was to meet situations like this that the outer end sections of the conveyor 200 are made detachable. As shown in Fig. 1, end section 220 has been attached. Limit stops 210 are swung out of the path of the boxes and the boxes are placed on the rear end of conveyor 200 and descend by gravity over the rollers and out over extension 220 where they are removed and placed on the floor or on the low stack. After the stack has reached a sufficient height the section 220 can be detached and the car 700 brought down to the bottom so that the stacking operation may proceed from there on by using elevator 400 and transport 600.

Tower 300

The tower serves as support and guide for the

mechanism of the elevator 400. It is square in horizontal section with the front side of the square left open as can be seen in Fig. 3. For convenience in transporting the stacker the upper part of the tower is detachable at the plane of section line 3—3 in Fig. 2.

The rear posts of the lower part of the tower are angles 304, 305 (Fig. 2). The bottom end of each angle is bolted to the rear transverse angle 137, as by means of a bracket indicated at 306 in Fig. 6. The upper ends of posts 304, 305 (Fig. 2) are welded to a transverse angle 307 which is also welded to the longitudinal angles 308, 309 (Figs. 1 and 3). The front ends of angles 308, 309 are welded into channels 310, 311 which have racks 312, 313 secured thereto by screws 314 (Fig. 6). Channels 310, 311 are the front posts of the lower part of the tower and their lower ends are welded to plates 315, 316 (Figs. 6 and 7). Plate 315 is bolted to transverse angles 136, 141; and plate 316 is bolted to transverse angles 136, 140. A pair of braces 320 (Fig. 1) are secured at their upper ends to angle 309 and at their feet to the base frame. A similar pair are attached to angle 308 on the other side of the tower (Fig. 2).

The base of the upper part of the tower is constructed of a transverse angle 330 (Fig. 2) welded to two longitudinal angles whose horizontal flanges lie on top of the horizontal flanges of angles 332, 333 (Fig. 3) and are detachably secured thereto by bolts 331. One of these longitudinal angles 332 can be seen in Fig. 1. The front ends of these angles are welded into vertical channels 331, 351, which are in alignment with channels 310, 311, and have racks 362, 363 secured thereto as continuations of racks 312, 313.

Channels 360, 361 extend vertically to the top of the tower and at progressively decreasing intervals pairs of longitudinal angles 340, 341, 342, similar to angles 332, are welded therein and extend rearwardly to transverse angles 343, 344, 345 (Fig. 2), to which they are welded. Vertical angles 350, 351 are welded to transverse angles 330, 343. Vertical angles 352, 353 are welded at the bottom to longitudinal angles 346, at the top to transverse angle 344. Vertical angles 354, 355 are welded at the bottom to longitudinal angles 341, at the top to transverse angle 345.

As can be seen in Fig. 1, pairs of crossed tie-rods 380, 381, 382 are used to stiffen the framework of the upper part of the tower. Similar tie-rods are employed on the other side.

Elevator 400

The elevator consists of eight vertical tubes to which tines are welded. The boxes are handled by these tines.

These eight tubes are disposed in the tower as shown in Fig. 3. Elevator tines 401 are on tubes 421, 422, 423, 424. These tubes intermittently reciprocate vertically in unison. Rest tines 402 are welded to rest tubes 431, 432, 433, 434. The boxes rest on tines 402 during the return reciprocatory stroke of the elevator tubes. Each set of four tubes is periodically rotated 90° to render their tines operative or inoperative in a manner presently to be described.

The tubes are guided in bearings mounted on the longitudinal angles of the tower. Tubes 423, 433 (Fig. 3) have bearings 450, 451, 452, 453 (Fig. 2); tubes 424, 434 (Fig. 3) have bearings 454, 455, 456, 457; and so on, tubes 421, 431, and 422, 432 at the front of the tower (Fig. 3) being provided with similar bearings, such as 458, 459.

It will be recalled that the tower is constructed to be knocked down for transportation, the two sections being bolted together at section 3—3 in Fig. 2. At this same plane the tubes are separable as shown in Fig. 4. Tube 421, for example, is in two parts. A guide plug 425 is secured in the bottom of the upper piece. Tube 431 has been separated to show its plug 435 projecting therefrom. As shown in Figs. 3 and 4, a tongue and groove driving connection is made at the parting. The plug facilitates joining the two parts of the shaft and stiffens the connection.

In order not to confuse the description the same reference numeral is used on both parts of each tube.

As shown in Fig. 13 the elevator tubes 421, 422, 423, 424 are in their up stroke and their tines 401 are turned inwardly to carry the box B thereon upwardly. The length of the reciprocatory stroke of the elevator tubes exceeds the vertical distance between the sets of rest tubes 402 so that at the top of the stroke the tubes 431, 432, 433, 434 may be rotated to swing their tines inwardly. At the beginning of the return stroke of the elevator tubes the box B is left resting on rest tubes 402, as shown in Fig. 14. As soon as the tines 401 release the box they are swung outwardly by rotation of the elevator tubes during the down stroke and at the end of the stroke they are swung in again. The box is again lifted, the rest tubes swinging out of the way until the end of the stroke when they swing in again to hold the box during the return stroke of the elevator tubes. In this manner the box is passed from one set of elevator tubes to the next set above, thus advancing the box upwardly by an intermittent motion. When the box is to be lowered in the elevator the driving mechanism is simply reversed so that elevator tubes 421 are in on the down stroke and out on the up stroke, the rest tubes 402 being timed to swing in and hold the box during the idle stroke of the elevator tubes. The mechanism for effecting these movements will now be described.

Elevator drive 500

The driving mechanism supplies the power for lifting or lowering the boxes and imparts the required movements to the two sets of tubes at the proper times. As can be seen in Fig. 3, half the tubes are on one side of the tower and the remainder are on the other side. The driving mechanism for tubes 421, 422, 423, 424 is substantially a duplicate of the driving mechanism for tubes 432, 433, 434 on the other side of the tower so a description of one driving mechanism will suffice.

The driving mechanism 500 (Fig. 1) is disposed under the tower 300 in the vehicle 100. It consists broadly of a crank and connecting rod to reciprocate the elevator tubes and racks to oscillate the tubes operated from a cam on the crank.

Referring now to Fig. 4, a head 501 is clamped to the elevator tubes 421, 423. The tubes are free to rotate in the head 501, but are prevented from axial movement relative thereto by collars 502, 503 attached to tube 421 and collars 504, 505 attached to tube 423. Head 501 has a pivotal connection 506 with a connecting rod 507 (Fig. 1) pivoted to crank pin 508 of crank 509 keyed to shaft 510. Shaft 510 extends across to the other side (Figs. 6, 7, and 9) where a similar crank 511 is keyed thereto having crank pin 512 for connecting rod 513 which reciprocates the elevator shafts 422, 424.

Referring again to Fig. 4, the bottom ends of elevator shafts 421, 423 are fitted with keys to engage keyways 520, 521 in tubes 522, 523, respectively. As shown in Fig. 5, the tube 423 is slotted to receive a key 524 held by screws 525 to a curved plate 526 fastened by screws 527 (Fig. 4) to tube 423. Key 524 (Fig. 5) slides in keyway 521 of tube 523. Tubes 522, 523 do not reciprocate but are provided with segmental gears 530, 531 for engagement with racks by which the tubes are periodically oscillated, the oscillatory movement being transmitted through the keys to shafts 421, 423 during their reciprocatory movement.

Rest tubes 431, 433 do not reciprocate, they merely oscillate to swing their tines 402 under the boxes or away, as needed. Accordingly, tubes 532, 533 are welded to the ends of rest tubes 431, 433 and are provided with gear segments 534, 535 which engage with racks to impart the oscillatory movements thereto.

Oscillating tubes 522, 532, 523, 533 have bearings 536, 537, 538, 539 at their feet. These bearings (Fig. 6) are mounted on the horizontal flange of longitudinal angle 107 (Fig. 7). Similarly, the bearings for the oscillating tubes on the other side of the machine are mounted on longitudinal angle 108.

Fig. 11 shows the bearing construction and mounting. The cages of the bearings, such as 536, 537, are welded to a plate 540 to establish the required center to center spacing. The outer race of the ball bearing is held in the cage by clamps 541, 542, the latter being common to both bearings 536, 537. The inner race is held against the bottom of tube 532 by a screw 545. The bolts 543, 544 of clamps 541, 542 pass through plate 540 and the horizontal flange of angle 107. In this same manner the four oscillating shafts on 107 and the four on 108 are supported for oscillation but are restrained from axial movement.

The gear segments 530, 531, 534, 535 (Fig. 4) are engaged by horizontally reciprocating racks. Gear segments 530, 531 for oscillating the elevator tubes are disposed in the same horizontal plane, while 534, 535 for the rest tubes are in a lower plane. As can be seen in Fig. 10, the racks for the elevator tubes are in the upper plane. These elevator racks 550, 551 engage gear segments 530, 531 (Fig. 4). In the lower plane (Fig. 10) are rest racks 554, 555 which engage gear segments 534, 535 (Fig. 4). Since the elevator tubes are to be oscillated in unison racks 550, 551 are fastened rigidly together in parallelism by means of end blocks 556, 557 to which they are secured by screws 558 and by means of straps 559. Rest racks 554, 555 are similarly fastened together for the rest tubes also oscillate in unison. Elevator racks 550, 551 are arranged on opposite sides of the vertical plane of the elevator tubes so that when the racks reciprocate the tubes 421, 423 will oscillate in opposite directions to swing the tines in and out as illustrated in Figs. 13 and 14. Likewise racks 554 and 555 are arranged on opposite sides to oscillate rest tubes 431, 433 oppositely.

Angle pieces, such as 560 (Fig. 10), are secured to channel end supports 561, 562 which are flanged at the base for securing to the frame of the vehicle. Channel 561 is secured at 563 (Fig. 9) to transverse frame channel 110 and channel 562 is secured at 564 to channel 109. As can be seen in Fig. 6, angles 560 provide guide ways in which the rack bodies slide. Elevator

rack 550 has a roller 565 and rest rack 554 has a roller 566. These rollers follow a cam track 567 (Fig. 1) formed on the inside of elevator crank 509. A similar cam track 568 (Fig. 6) is formed on the inside of the crank for elevator connecting rod 513 which is located on the other side of the machine. The nest of racks 550, 551, 554, 555 are adjacent 567 and a similar nest of racks on the other side are adjacent 568.

The arrangement of the cams, racks, and segmental gears on the oscillating shafts can also be seen in Fig. 9 where it will appear that upon rotation of common drive shaft 510 connecting rods 507 and 513 will operate to vertically reciprocate the elevator tubes and at the same time the cam track 567 will, by engagement with the followers 565, 566, cause reciprocation of the elevator and rest racks to oscillate the elevator and rest tubes to bring their tines into and out of play as described.

Broadly, the configuration of the cam track, indicated in dotted lines in Fig. 1, is a short throw and a long throw interconnected by paths to give smooth acceleration and deceleration from the two extreme positions. The path of short radius is 570 and the follower 565 is disposed therein in the particular position shown. The other follower 566 is disposed in the path of long radius 571. In this position of the cam the elevator racks connected to 565 are shifted toward the front of the stacker to hold elevator tines 401 outwardly from the center of the tower as shown. And the rest racks connected to 566 (which is in short radius path 570) are also shifted toward the front of the stacker to hold rest tines 402 inwardly in their box supporting position. This relationship can also be seen in Fig. 9 where the short-radius path 570 is positioned nearer the axis of shaft 510 than the long-radius path 571. The upper racks 550, 551 appear at the left of the figure but are broken away at the right to show the lower racks 554, 555 underneath. The connection between roller 565 and rack 550 is also broken away because this roller is on the upper rack 550 as shown in Fig. 10. As shown in Fig. 9, the upper or elevator racks 550, 551 are shifted toward the front of the stacker and due to their engagement with segmental gears 530, 531, the elevator oscillating tubes have been rotated as follows: 523 clockwise; 522 counterclockwise. This has resulted in swinging the elevator tines 401 (shown dotted) outwardly. The lower or rest racks 554, 555 are also shifted to the right due to roller 566 being in short-radius path 570 of the cam, and by engagement with gear segments 534, 535 have rotated oscillating shafts 532, 533 as follows: 532 counterclockwise; 533 clockwise. This has resulted in swinging rest tines 402 (shown dotted) into their box supporting positions as shown. It will be noted that the racks and tines on the opposite side of the machine have taken up corresponding positions.

Now referring to Fig. 1, if the drive shaft 510 is rotated counterclockwise the elevator will lift boxes. First roller 565 will leave long-radius path 571 and enter short-radius path 570. This will cause the elevator racks to shift toward the rear of the machine, swinging elevator tines 401 in, bottom tines 401 swinging under box B resting on conveyor 200. Crank pin 508 will meanwhile have passed through bottom dead center and will start to lift the elevator tubes bringing tines 401 into engagement with the box and lifting it up off the conveyor. If there are other

boxes in the elevator the tines 401 will at this same time lift the boxes up off the rest tines 402. Next the follower 566 will enter the long-radius path 571 causing the rest racks to shift rearward and swing rest tines outwardly so that they will not obstruct the upward movement of the boxes which the elevator tines are lifting.

As crank pin 508 approaches top dead center follower 566 leaves path 571 for path 570, causing the rest racks to shift forward and swing rest tines 402 inward. This is possible because the length of the stroke of the elevator tubes exceeds the vertical spacing of the rest tines 402. After the crank pin 508 passes through top dead center the elevator tubes begin to descend and the elevator tines 401 lower the boxes onto the rest tines 402 which have just been swung in. Thereupon the follower 565 enters the long-radius path 571 shifting the elevator racks forward and swinging elevator tines 401 out so that as they descend in the return stroke they may pass by the boxes which are resting on tines 402. With each revolution of drive shaft 510 the elevator tines pick up another box from the conveyor 200 and raise the boxes in the elevator to the next set of rest tines 402.

The cam is reversible so that by reversing shaft 510 the elevator operates to lower boxes step by step until they are deposited one by one on conveyor 200 which conducts them out of the stacker. Taking the position shown in Fig. 1 as the starting position again, with elevator tines out and rest tines in, the shaft 510 is rotated clockwise. Crank pin 508 is leaving its bottom dead center and the elevator tubes are rising, tines 401 being out, are carried upward past boxes in the elevator resting on tines 402. As crank pin 508 approaches top dead center follower 565 leaves path 571 and elevator tines 401 swing in and lift the boxes off the rest tines. As crank pin 508 passes through top dead center follower 566 enters path 571, causing rest tines 402 to swing out. Follower 565 remains in path 570 during the down stroke so that tines 401 remain in and lower the boxes. As the crank pin 508 approaches bottom dead center follower 566 enters path 570, swinging rest tines 402 in to receive the boxes. The tines 401 lower the boxes onto the rest tines 402 and the bottom box is lowered onto the conveyor 200.

To control the entrance and exit of boxes at the bottom of the elevator there is a gate 430 (Fig. 1) comprising a pair of brackets 481, 482 attached to the reciprocating heads 501 and supporting a roller 483 (Fig. 2) which contacts the box ends. Gate 430 moves up and down with the elevator tubes so that on each stroke another box is admitted to the elevator or released therefrom, depending on whether the stacker is raising or lowering boxes.

It will be recalled that there is a transport 600 (Fig. 1) up on the tower which transports the boxes out of or in to the elevator at the top of the stack. This transport has a shifter 601 which is driven in synchronism with the elevator. The driving mechanism therefor will now be described.

A vertical splined shaft 572 (Fig. 1) is supported at the top of the tower in a bearing 573 mounted in a bracket 574 secured to longitudinal angle 342 (Fig. 2) on the left side of the stacker. The foot of shaft 572 (Fig. 6) is supported on a ball bearing 575 and is held in a plain bearing 576. A bevel gear 579 is secured to the end of shaft 572. Bearing 576 is fastened by bolts 577 to bracket 579 which is secured to transverse frame angle 136. Bevel gear 579 meshes with bevel gear

580 (Fig. 12) secured to shaft 581 which is mounted in bearings 582, 583. Bearing 582 is bolted to a depending arm of bracket 578, and bearing 583 is fastened to a bracket 584 (Fig. 9) which is fastened to a vertical angle 585 secured to transverse angles 135 and 109. A sprocket 586 (Fig. 12) is keyed to shaft 581 and driven by chain 587 (Fig. 9) from sprocket 588 keyed to shaft 510 which drives the elevator mechanism.

Main drive shaft 510 is driven from a reversible electric motor 589 which has a bevel pinion 590 meshing with bevel gear 591 keyed to shaft 592 supported in bearings 593, 594. The other end of shaft 592 has a spur pinion 595 keyed thereto which meshes with spur gear 596 keyed to main drive shaft 510. Bearing 593 (Fig. 7) of shaft 592 is fastened to longitudinal angle 115 of the main frame and bearing 594 is fastened to angle 125 of the sub-frame.

Reversal of motor 589 causes reversal of main drive shaft 510 and the reversal of the mechanism driven thereby, namely, the elevator drive and the transport drive.

Transport 600

The vertical splined shaft 572 (Fig. 29) has a bevel gear 610 which is axially slidable thereon. Gear 610 has a bearing 611 secured in the framework of the car 100 so that as the car moves up and down the tower the bevel gear 610 slides along the shaft 572 but maintains a driving connection therewith by means of a key 612. Bevel gear 610 meshes with bevel gear 613 keyed to shaft 614 mounted in bearings 615, 616 fastened to the car framework. A sprocket 617 is keyed to the other end of shaft 614. Sprocket 617 is connected by a chain 618 (Fig. 1) with a sprocket 619 on cam shaft 620 which is journaled in bearings 621, 622 (Fig. 16) mounted on the framework of the car.

The hub 623 of a double cam is keyed to shaft 620. One side is an external cam 624 upon which a roller 625 rides; on the other side is formed a cam track 626 with which a roller 621 (Fig. 15) engages. Fig. 18 shows diagrammatically the drive from reversible motor 589 through bevel gears 590, 591 to shaft 592 through gears 595, 596 to main drive shaft 510 which carries elevator cranks 509, 511, thence from sprocket 588 through chain 587 to sprocket 586 on shaft 581 connected by bevel gears 580, 589 to splined shaft 572 having bevel 610 on it in car 100 and from bevel 610 to bevel 613 to shaft 614 and sprocket 617 through chain 618 to sprocket 619 on shaft 620 to double cam 624, 626. Reversal of motor 589 causes reversal of cams 624, 626.

Cams 624, 626 actuate the box shifter 601 (Fig. 16) which is a platform that is projected into the elevator through its front or open side and under the box, lifting the box off its tines and then withdrawing the box out of the elevator and depositing it on the rollers of the conveyor.

The cam follower 625 is pivotally mounted at the foot of an angle 630 (Fig. 16) which is welded to a transverse angle 631, to the horizontal flange of which longitudinal angles 632, 633 are welded. These angles extend the length of the transport as shown in Fig. 15. At their forward ends they have small depending plates, such as 634, welded thereto, which plates have pivotal connection 635 with longitudinal angles 710, 711 of the car framework. Thus cam 624 causes this oscillating frame composed of members 630, 631, 632, 633, 634 to rock on its pivot 635. Vertical guide plates 636, 638 are provided at the rear end.

Plate 636 is welded to a bracket 637 bolted to angle 710, and plate 638 is welded to a bracket 639 bolted to angle 711.

A carriage for the shifter is carried by the oscillating frame and reciprocates thereupon. This carriage is constructed of two castings 640, 641 (Fig. 15) secured by pins 642 to a pair of rods 643, 644 (Fig. 16). The rods 643, 644 slide in bearing brackets 645, 646 which are mounted on the angles 632, 633 (Fig. 17) of the oscillating frame.

Cam 626 reciprocates this carriage. Follower 627 (Fig. 15) is on an arm 647 secured to a shaft 648 supported in the car framework. Another arm 649 is secured to shaft 648 and is pivotally connected at 650 to a link 651 which is pivotally connected to a shaft 652 mounted in depending portions 653, 654 (Fig. 16), of casting 641 of the carriage. When cam 626 rotates, bell crank 647, 649 causes the carriage to reciprocate on the oscillating frame, rods 643, 644 of the carriage sliding in bearings 645, 646 on the oscillating frame.

The shifter platform 601 reciprocates on the carriage. Platform 601 has a skirt in the end walls of which rods 655, 656 are secured. Rods 655, 656 slide in bearing holes in castings 640, 641. Platform 601 has a pair of racks 657, 658 welded to its under side. Racks 657, 658 mesh with gears 659, 660, respectively, which are mounted on the hubs of pinions 661, 662 and secured against movement relative thereto by set screws. Pinions 661, 662 are mounted on the ends of shaft 652 which is supported in carriage casting 641. Pinions 661, 662 engage racks 663, 664 welded to angles 633, 632 of the oscillating frame. Thus when the carriage is reciprocated by bell crank 647, 649 the pinions 661, 662 roll on the racks 663, 664, and the gears 659, 660 drive the racks 657, 658, thereby imparting a long stroke to the platform 601 as compared with the short stroke of the carriage. There is also a proportional speed differential which is advantageous because the shifter has to enter the elevator, pick up the box, and withdraw as rapidly as possible. Some idea of the relative speeds can be had by considering that rack 664, being the locus of the instantaneous centers of rotation of pinion 662, a point on the pitch circle diametrically above the instantaneous center has twice the linear speed of the pinion center (or shaft 652), so that if rack 658 engaged directly with pinion 662 it would move twice as fast as the carriage. But there is a further speed increase due to the gear 660, so that the speed of the rack 658 (and platform 601) is equal to the ratio of the radii of gear 660 and pinion 662 multiplied by two.

Figs. 31 to 34 diagrammatically illustrate the action of the shifter. The reference numerals will be found applied to the corresponding actual parts in Fig. 15. Note that 710 and 635 remain fixed throughout Figs. 31 to 34 while the other parts move. In Fig. 31 reciprocating parts 601 and 644 are at the forward end of their stroke and oscillating frame 632 is in the down position. In Fig. 32, 632 is still down but 644 has reached the rear end of its stroke and so has 601 which has moved further than 644 due to gear 660, etc. In Fig. 33 oscillating frame 632 has moved up. In Fig. 34, 632 is still up but 601 is at the forward end of its stroke. The next position is that shown in Fig. 31. When the cams are reversed the cycle of 601 is reversed. It begins with the position shown in Fig. 31 and then pro-

ceeds through the position shown in Figs. 34, 33, 32, 31, in the order named.

At the forward end of its stroke the shifter 601 (Fig. 1) either deposits the box on conveyor 602 or removes the box therefrom, depending on the direction in which the stacker is being operated. The boxes can be removed from the end of conveyor 602 to the stack or they can be transferred to a swinging conveyor such as is sometimes used in warehouses to distribute boxes in radial directions from a central discharge point.

Conveyor 602 comprises roller discs 670 (Fig. 16) pivotally mounted on the inside of rails 671, 672 which are supported on their rear ends on brackets 637, 639 and at their front ends on brackets 673 (Fig. 15) and 674 (Fig. 1). End stops 675, 676 (Figs. 15 and 16) are secured to the rear ends of rails 671, 672 to prevent movement of boxes into the elevator by conveyor 692. These stops also serve to position boxes entering the elevator for shifter 601 to pick them up.

Figs. 19 to 27 illustrate the timing of the elevator and shifter. Fig. 19 represents the parts in the relative positions they occupy in Fig. 1. It will be recalled that drive shaft 510 has a crank 509 and crank pin 508 which vertically reciprocate elevator tubes 421, 423, and that a cam 567 is formed integrally with crank 509 to shift racks by means of followers. Follower 565 operates elevator racks 550, 551 to oscillate elevator shafts 421, 423 to swing elevator tines 401 in and out, and follower 566 operates rest racks 554, 555 to oscillate rest shafts 431, 433 to swing rest tines 402 in and out. Shaft 510 is rotated clockwise to lower boxes and counterclockwise to lift boxes. If the motion is counterclockwise the next position of the parts is shown in Fig. 20 where elevator tines 401 are swinging in under box B1 on rest tines 402, and shifter 601 is removing box B2 from the elevator. Shifter 601 is up and moving forward. In Fig. 21 elevator tines 401 are lifting box B1 up off rest tines 402, and shifter 601 has removed box B2 farther from the elevator. In Fig. 22 the elevator tines 401 are lifting box B1, rest tines 402 have swung out, and shifter 601 is nearing the end of its forward stroke in the up position. In Fig. 23 elevator tines 401 are nearing the top of their stroke, as indicated by the proximity of crank pin 508 to top dead center. The tines 401 have lifted box B1 above rest tines 402. Shifter 601 has lowered box B2 onto conveyor 602. In Fig. 24 the rest tines 402 are swinging in under the box B1 while elevator tines 401 are at the top of their stroke, crank pin 508 having arrived at top dead center. Shifter 601 is starting its rearward stroke in the down position. In Fig. 25 the elevator tines 401 have started their down stroke and have left box B1 on rest tines 402. Shifter 601 is entering under box B1. In Fig. 26 elevator tines 401 are still descending, having swung out, and shifter 601 has moved farther under box B1 on rest tines 402. In Fig. 27 elevator tines 401 are still descending and being in the out position are clearing box B1. Shifter 601 is at the end of its rearward stroke in the down position. The next step is Fig. 19 again where shifter 601 lifts the box off rest tines 402. This cycle is completed with each revolution of drive shaft 510, a box being removed from the elevator at each revolution.

When drive shaft 510 rotates clockwise (Fig. 19) the cycle is reversed. The next position is Fig. 27 where shifter 601 has deposited box B1 on rest tines 402. Elevator tines 401 are rising (see crank pin 508) and are passing by the

boxes. In Fig. 26 the shifter 601 is withdrawing from the elevator. In Fig. 25 elevator tines 401 have swung under box B1. In Fig. 24 they have lifted it off rest tines 402. In Fig. 23 rest tines 402 have swung out and shifter 601 is under box B2. In Fig. 22 elevator tines 401 are lowering box B1 and shifter 601 has picked up box B2. In Fig. 21 rest tines 402 have swung under box B1 and shifter 601 is carrying box B2 into the elevator. In Fig. 20 elevator tines 401 have deposited box B1 on rest tines 402 and are swinging out. In Fig. 19 elevator tines 402 are out and are starting to rise. Shifter 601 has reached the rear end of its stroke ready to deposit the box on rest tines 402.

Car 700

The transport 600 which transports the boxes from the elevator across to the stack is mounted in a car 700 which can be moved up and down the tower 200 to a plurality of operative stations.

It was for this purpose that the front channels 360, 361 (Fig. 28) of the tower were provided with vertical racks 362, 363. Pinions 720, 721 keyed on shaft 722 engage racks 362, 363. Shaft 722 is mounted in bearing brackets 723, 724 (Fig. 2) which are secured to longitudinal channels 725, 726 of the car framework. Shaft 722 projects beyond bearing 724 and gear 727 is secured to the end of the shaft. Gear 721 (Fig. 28) is driven by pinion 728 on shaft 729 having gear 730 driven by pinion 731 on a worm shaft driven from motor 732. Motor 732 is equipped with a magnetic brake 733 to hold the car in place when the motor is not running. Operation of the motor, which is reversible, causes car 700 to climb or descend.

The car is held to the channels 360, 361 by sheaves 734, 735 engaging flanges 364, 365 of the channels and rollers 736, 737 engaging the front faces of the channels. These sheaves and rollers are mounted on longitudinal channels 725, 726 (Fig. 2) and a similar set are mounted on longitudinal angles 738, 739.

The car is provided with a suitable floor 740 (Fig. 1) and railing 741 to provide a place for the operator to stand. He controls the movement of the car by an electric control 850 for car motor 732. He can also stop the shifter and elevator by operating the rod 830 which runs down to a control 831 which stops motor 589.

The various electrical controls will now be described.

Electrical controls 800

The location of these controls is shown in Figs. 36 and 37 and the wiring diagram therefor is in Fig. 38.

The three lines of the power main 803, 804, 805 (Fig. 38) are connected to one side of switch 806 and also by lines 807, 808, 809 to one side of switch 810. The opposite sides of these two switches are connected to lines 811, 812, 813 of motor 589. When switch 806 is closed the connections are as follows: 803—811; 804—812; 805—813. To reverse motor 589 switch 810 is closed connecting 803 to 813 through 807; 804 to 812 through 808; 805 to 811 through 809. Lines 814, 815 from 813, 812 are for energizing a magnetic brake on motor 589.

Switches 806, 810 are actuated by solenoids 816, 817 which also actuate switches 818, 819.

These switches have a common arm 824 pivoted at 825 so that when solenoid 816 is energized arm 824 is rotated counterclockwise to open switch

819, and vice versa. Switch 818 is connected by line 826 to solenoid 816 and switch 819 is connected by line 827 to solenoid 817. The other sides of the solenoids are connected through switches 821, 822 to line 823 which is connected to power line 803. The arm 824 of switches 818, 819 is connected through switches 803A and 831 in series to line 820 which is connected through circuit breaker 821 to line 822 connected to power line 804.

When the operator presses the button of switch 801 solenoid 816 closes switch 806 and motor 589 rotates in a direction to cause the boxes to be lifted by the elevator and removed therefrom by the shifter. If he presses the button of switch 802 solenoid 817 closes switch 810 and motor 589 rotates in the opposite direction causing the shifter to deposit boxes in the elevator which then lowers them. The elevator is stopped by pressing the button of stop switch 803 or by opening switch 831.

The "up" and "down" and "stop" buttons are on control box 800 (Fig. 36) in which are located solenoids 816, 817 and switches 806, 810. Switch 831 is in a separate box at the foot of its operating rod 830.

The "up" and "down" and "stop" controls for the car motor 732 (Fig. 38) are substantially the same as those for motor 589. When the operator presses the button of switch 851 solenoid 854 closes switch 856 to cause motor 732 to move the car up. When he presses the button of switch 852 solenoid 855 closes switch 857 to cause the motor to move the car down. He only uses switch 853 to stop the car in case of emergency because switch 858 automatically stops the car at each station.

Switch 858 (Fig. 37) is mounted on the back of the car and is actuated by the actuators 853 to 856 at each station. The actuators are fixed to the tower. Also on the tower are top limit stop switch 884 and bottom limit switch 885, which are actuated by actuators 886, 887, respectively, attached to the top and bottom of the car. Switches 884, 885 (Fig. 38) are in series with solenoids 854, 855, respectively.

The solenoid circuit receives its power through lines 861, 868 from power lines 871, 872. There is a switch 869 in line 868 which is only closed when the shifter is in its forward position. Lever 649 (Fig. 37) of the shifter has a switch actuator 870 secured thereto which holds switch 869 closed as long as the shifter is in its forward position, that is, withdrawn from the elevator. This switch acts as an interlock between the box handling mechanisms and the car so that the car cannot be moved while the elevator and shifter are working.

The "Up" and "Down" and "Stop" switches 851, 852, 853 are located at 871 on the car, and the solenoids 854, 855 and switches 856, 857 are located in box 875 under the car. A circuit breaker 821 is located on the front of the vehicle. It is energized from lines 873, 874 (Fig. 38) in the circuit of car motor 732 and it acts as another interlock, preventing the operation of elevator motor 589 while car motor 732 is working.

Permanent installation

The construction of the elevator readily adapts itself to installation in a building as a permanent elevator.

In Fig. 39 such an installation is shown diagrammatically. Building 920 has a ground floor 921 and upper floors 902, 903, 904. The elevator

403, comprising the elevator tubes with their tines 401 and the rest tubes with their tines, is supported in the floors of the building, or in an enclosed shaft if desired, in the same manner in which it is supported in tower 389. The driving mechanism 500 is under the elevator 400 in exactly the same position it occupied relative thereto in the stacker.

Instead of having only one transport 600 in a car, each floor 902, 903, 904 would have its individual transport. These transports would each have its shifter 601 and conveyor 602 and would be in every respect substantially identical with that in the stacker except that a clutch 905 (Fig. 35) would be placed in each shaft 614. Comparison of Fig. 35 with Fig. 18 will show that the driving mechanisms are otherwise the same. A bevel 610 would be placed on vertical shaft 572 at each floor to drive the shaft 614 of each shifter. The clutch 905 merely enables the transport 600 selected for use to be put into operation so that the boxes could be automatically removed from the elevator 400 (Fig. 30) at any floor. The conveyor 200 would be located at the bottom of the elevator as before. Thus the permanent installation differs from the mobile stacker only in the duplication of transports 600 and the provision of a separate driving gear 610 and clutch 905 for each.

While we have shown and described two forms of the invention, it is to be understood that it is capable of variations and changes from the embodiments shown without departing from the spirit or scope of the invention.

We claim:

1. An elevator for handling boxes and the like comprising a plurality of reciprocatory tubes having elevator tines thereon, a plurality of tubes having rest tines thereon, a drive shaft, a crank connected to said shaft for reciprocating said elevator tubes, cam means connected to said shaft, a rack and pinion for oscillating each of said tubes, certain of said racks and pinions being operated by one portion of said cam means for oscillating said rest tine tubes, and other of said racks and pinions being operated by an opposite portion of said cam means for oscillating said elevator tine tubes in timed relation with said rest tine tubes.

2. An elevator for handling boxes and the like comprising a plurality of reciprocatory tubes having elevator tines thereon, a plurality of tubes having rest tines thereon, a drive shaft, a crank connected to said shaft for reciprocating said elevator tubes, cam means connected to said shaft, a rack and pinion for oscillating each of said tubes, said racks and pinions being operated by said cam means, said crank and cam means being constructed to cause reverse operation of the elevator upon reverse rotation of said drive shaft.

3. In a box elevator having elevator tines for moving boxes vertically and rest tines for supporting boxes when they are not being moved by said elevator tines, a shifter to remove boxes from said elevator when the boxes are on said rest tines, a carriage for said shifter, means to raise and lower said carriage, and means to reciprocate said shifter with respect to said carriage.

4. In a box elevator having elevator tines for moving boxes vertically and rest tines for supporting boxes when they are not being moved by said elevator tines, a shifter to remove boxes from said elevator when the boxes are on said

rest tines, a support, and a carriage slidably mounted on said support, said shifter being slidably mounted on said carriage.

5. In a box elevator having elevator tines for moving boxes vertically and rest tines for supporting boxes when they are not being moved by said elevator tines, a shifter to remove boxes from said elevator when the boxes are on said rest tines, a movable support, a carriage slidably mounted on said support, said shifter being slidably mounted on said carriage, and cam means operative to raise and lower said support and to slide said carriage on said support.

6. In a box elevator having elevator tines for moving boxes vertically and rest tines for supporting boxes when they are not being moved by said elevator tines, a shifter to remove boxes from said elevator when the boxes are on said rest tines, a support, a carriage slidably mounted on said support, said shifter being slidably mounted on said carriage, and means to actuate said shifter including a rack on said support, a rack on said shifter, and gears pivotally mounted on said carriage and engaging said racks.

7. In a box elevator having elevator tines for moving boxes vertically and rest tines for supporting boxes when they are not being moved by said elevator tines, a box shifter, a carriage for said shifter, a support for said carriage, means to raise and lower said support so as to position the box-engaging surface of said shifter in a plane below the rest tines on which the box is resting when said support is lowered and in a plane above said tines when said support is raised, and means to reciprocate said shifter on said carriage so that said shifter is projected into the elevator in said lower plane and is withdrawn therefrom in said upper plane.

8. In a box elevator having elevator tines for moving boxes vertically and rest tines for supporting boxes when they are not being moved by said elevator tines, a box shifter, a carriage for said shifter, a support for said carriage, means to raise and lower said support so as to position the box-engaging surface of said shifter in a plane below the rest tines on which the box is resting when said support is lowered and in a plane above said tines when said support is raised, means to reciprocate said shifter on said carriage so that said shifter is projected into the elevator in said lower plane and is withdrawn therefrom in said upper plane, and box-engaging means adjacent said shifter adapted to remove the box from said shifter when said support is lowered.

9. In a box elevator having elevator tines for moving boxes vertically and rest tines for supporting boxes when they are not being moved by said elevator tines, a box shifter, a carriage for said shifter, a support for said carriage, means to raise and lower said support so as to position the box-engaging surface of said shifter in a plane below the rest tines on which the box is resting when said support is lowered and in a plane above said tines when said support is raised, means to reciprocate said shifter on said carriage so that said shifter is projected into the elevator in said lower plane and is withdrawn therefrom in said upper plane, and a row of discs mounted on said support along each side of said shifter, a plane tangent to the tops of said discs being intermediate said upper and lower planes of travel of said shifter.

10. In a box elevator, elevator members having elevator tines thereon, rest members having

rest tines thereon, means including a crank for reciprocating said elevator members, and means for oscillating said elevator and rest members to move said tines into and out of box-engaging position, including a cam associated with said crank having a long-radius portion and a short-radius portion, two cam followers, one for said elevator members, the other for said rest members, means to oscillate said elevator members actuated by one of said followers, means to oscillate said rest members actuated by the other of said followers, said two oscillating means and said two followers being arranged so that said elevator tines are in box-engaging position when said elevator follower is in contact with one of said cam portions and so that said rest tines are in box-engaging position when said rest follower is in contact with said same cam portion.

11. A mechanism for shifting articles from one place to another comprising, a shifter adapted to be brought into carrying engagement with the article, a carriage for said shifter, means to reciprocate said shifter with respect to said carriage, a movable support for said carriage, means to reciprocate said carriage on said support, means to elevate said support operable to raise said support at one end of the reciprocatory stroke of said shifter to enable said shifter to pick up the article and operable at the other end of the stroke to lower said support to enable said shifter to set the article down.

12. A mechanism for shifting articles from one place to another comprising, a shifter adapted to be brought into carrying engagement with the article, a carriage for said shifter, said shifter being slidably mounted on said carriage, a movable support for said carriage, said carriage being slidably mounted on said support, means to reciprocate said carriage and said shifter, including motion-multiplying means to impart a longer stroke to said shifter than to said carriage, and means to elevate said support actuated in timed relation with said reciprocating means to raise said support at one end of the reciprocatory stroke of said carriage and shifter and to lower said support at the other end of the stroke.

13. A mechanism for shifting articles from one place to another comprising, a shifter adapted to be brought into carrying engagement with the article, a carriage for said shifter, said shifter being slidably mounted on said carriage, a movable support for said carriage, said carriage being slidably mounted on said support, means to reciprocate said carriage and said shifter, including motion-multiplying means to impart a longer stroke to said shifter than to said carriage, and means to elevate said support actuated in timed relation with said reciprocating means to raise said support at one end of the reciprocatory stroke of said carriage and shifter and to lower said support at the other end of the stroke, said elevating and reciprocating means including cam means reversible in operation to enable said shifter to move articles in either one direction or the other.

14. A mechanism for imparting a reciprocatory motion to a plurality of devices positioned on op-

posite sides of the axis of rotation of a drive element for operating said mechanism, comprising a cam on said drive element and rotatable about said axis, said cam having a long radius portion and an opposite short radius portion, a pair of members for engaging said devices, said members being positioned on opposite sides of said axis and extending transversely thereof substantially parallel to each other and being supported for substantially linear movement in said position, and a cam follower on each said member, said followers engaging opposite portions of said cam and one follower adapted to engage said long radius portion of said cam when the other engages the short radius portion thereof.

15. A mechanism for imparting a reciprocatory motion to a plurality of devices positioned about the axis of rotation of a drive member for operating said mechanism, comprising a cam on said drive member and rotatable about said axis, said cam having a long radius portion and a short radius portion, an elongated member having a cam follower engaged with said cam, a second elongated member having another cam follower engaged with an opposite portion of said cam, said elongated members being positioned on opposite sides of said axis and extending transversely thereof and said members being slidably supported lengthwise thereof on both sides of their respective followers for linear movement in said position, each of said elongated members engaging one of said devices positioned on one side of said axis and engaging a second device positioned on the opposite side of said axis, and one of said followers being adapted to engage the long radius portion of said cam when the other engages the short radius portion thereof.

16. A box elevator comprising a support forming an elevator shaft, a plurality of vertical rest members associated with said support and having horizontal rest tines extending therefrom, and spaced apart thereon to provide a plurality of box supporting stations at which boxes are to be shifted to and from said elevator, a plurality of vertical elevator members having horizontal elevator tines extending therefrom for supporting and conveying boxes to said stations, certain of said rest members and elevator members being positioned adjacent one side of said elevator shaft and others being positioned adjacent the opposite side of said elevator shaft, the distance between said opposite rest members and elevator members being such as to permit shifting of boxes to and from supporting engagement with said rest and elevator tines at each of said stations, means to oscillate said rest and elevator tines and in such manner that said tines assume a position generally normal to said sides when in box supporting position and assume a position generally paralleling said sides when clear of the boxes, and means for reciprocating said elevator members vertically whereby said elevator tines may convey boxes from one station to another.
